UNITED STATES PATENT OFFICE.

MASON W. HALL, OF SCHENECTADY, NEW YORK.

ARCH-SUPPORT.

1,064,902.

Specification of Letters Patent. Patented June 17, 1913.

Application filed June 30, 1911. Serial No. 636,206.

To all whom it may concern:

Be it known that I, MASON W. HALL, a citizen of the United States, residing at Schenectady, county of Schenectady, State 5 of New York, have invented certain new and useful Improvements in Arch-Supports, of which the following is a specification.

My invention has reference to a support 10 for the foot, and particularly, a support for the arch of the foot.

It is well known that the arch of the foot frequently breaks down causing great discomfort and even permanent injury. It 15 has hitherto been proposed to counteract this tendency by providing an arch of metal or other rigid material which is placed within the shoe and adapted to support the arch of the foot. Such arches, however, are 20 harsh upon the foot and do not conform closely to the configuration thereof with the consequence that they cause discomfort. It has also been proposed to use an arch support made of flexible material which rests 25 directly against the insole of the shoe. Such arch supports, however, do not furnish the firm support for the arch of the foot that is furnished by a rigid support; moreover, as such supports rest directly upon the 30 shank of the shoe, the shank is frequently broken down thereby ruining the shoe.

My novel form of arch support is so made 35 that it preserves the arch of the foot, and at the same time conforms perfectly to its configuration and forms a firm yet yielding support therefor, thereby avoiding the jarring and consequent fatigue which results from treading upon materials which are unyielding in their nature.

More specifically, my invention comprises 40 a rigid support together with a yielding support formed of an inflated envelop.

For a fuller understanding of my invention reference is had to the accompanying 45 drawings in which—

Figure 1 is a perspective view of a shoe which is broken away to show my novel form of arch support therein; Fig. 2 is a plan view; Fig. 3 is a longitudinal section 50 on the line 3—3 of Fig. 2; Fig. 4 is a section on the line 4—4 of Fig. 2; Fig. 5 is a section on the line 5—5 of Fig. 2; Fig. 6 is a section corresponding to Fig. 5 showing a modified form of arch support; Fig.

7 is a plan view of a modified form of my 55 invention; and Fig. 8 is a section on the line 8—8 of Fig. 7.

Referring first to Figs. 1 to 6, in which I have shown the preferred form of my invention, 1 is a shoe within which is shown 60 my novel form of arch support 2. The support is composed of an envelop 3 which is covered by a protective material 4, and a rigid support 5. The envelop 3 is preferably made of rubber and is so shaped as to 65 naturally conform to the shape of the foot. For this purpose, the space 6 between the upper and lower walls of the envelop which lies beneath the arch of the foot and on the inner side of the foot is usually thicker 70 than the remainder, from which portion the space within the envelop gradually tapers to the other side of the foot as best shown at 7 in Fig. 5 and toward the heel as shown at 8 in Fig. 3. From the arch the 75 envelop tapers toward the toe with the exception that a relatively thick portion is formed at 9 which lies beneath and supports the transverse arch of the foot, that is, the arch formed by the bones between 80 the ball of the foot and the little toe. The protective layer 4 is formed of canvas or other tough material which serves to protect the rubber envelop and at the same time helps to preserve the general configuration of the envelop. 85

An arch 5 which is made of steel or other rigid material is located beneath the envelop and the protective coating and is secured to the protective coating by rivets 90 as shown, or in any suitable manner. This rigid arch is so placed relatively to the other portions of the arch support that when placed in the shoe it lies beneath the arch of the foot. The envelop is provided 95 with a suitable valve 10 by which it may be inflated.

In Fig. 6 I have shown in section the preferred form of my arch support in which the inner edge of the envelop 3 and protective covering 4 are elevated at 12 so that the section is nearly triangular in form. In this form the inner raised edge of the support holds the flesh beneath the arch of the foot in position and prevents it from 105 protruding over the edge of the arch support.

In Figs. 7 and 8 I have shown a modifi-

cation of my invention in which the inflated portion of the arch support consists of a rubber tube 11, one end of which is suitably closed, while the other end is provided 5 with a valve 10 by which the tube may be inflated. The tube is so coiled that it substantially conforms to the outline of the foot as shown in Fig. 7. The tube after inflation may be surrounded, if desired, by 10 rubber which is cast about the tube and beneath which the rigid support is placed so that the general form of the completed support is substantially the same as that shown in Figs. 1 to 5.

15 It will be understood that my arch support is inflated before it is placed in the boot or shoe and is easily removable therefrom which is a great advantage in case the life of the arch support is longer than that 20 of the shoe, or in case it is desired to replace the same before the shoe is worn out.

While I have shown my cushion support extending from the heel to a point a little in advance of the transverse arch, it will be 25 understood that under some conditions it would extend throughout the bottom of the shoe while under other conditions it would be made shorter than the one shown and described.

30 While in accordance with the patent statutes, I have shown what I consider to be the preferred form of my invention, it will be understood that numerous changes could be made without departing from the spirit

thereof, and that my invention covers all 35 such changes and equivalents.

What I claim as new and desire to secure by Letters Patent of the United States is:

1. In an arch support, an elongated flexible pneumatic envelop shaped to conform 40 to the arch of the foot, and a rigid arch-shaped support located immediately beneath the envelop and extending longitudinally thereof to which the envelop closely conforms. 45

2. In an arch support, an elongated flexible pneumatic envelop shaped to conform to the arch of the foot and provided with a valve by which the envelop may be inflated, and a rigid metallic arch-shaped support 50 located immediately beneath the envelop and extending longitudinally thereof to which the envelop closely conforms.

3. In an arch support, an elongated flexible pneumatic envelop shaped to conform to the arch of the foot and provided with a valve by which the envelop may be inflated, a protective covering for said envelop, and a rigid arch-shaped support located immediately beneath the envelop to which the 55 envelop closely conforms. 60

In witness whereof, I have hereunto set my hand this 23 day of June 1911.

MASON W. HALL.
